UNITED STATES PATENT OFFICE

AUGUST FREDERIC CHRISTIANI, OF RED LODGE, MONTANA

DISPENSING DEVICE

Application filed April 1, 1931. Serial No. 526,902.

The present invention relates to article dispensing devices, and comprehends the provision of a novel construction primarily intended for singly delivering a cigarette from a receptacle upon each operation of the device.

In carrying out the invention I provide a lever actuated member constructed to pierce the end of an adjacent cigarette located within its receptacle, and to singly remove said cigarette upon reverse movements of the member.

The nature and advantages of the invention will be better understood when the following detail description is read in connection with the accompanying drawing, the invention residing in the construction, combination and arrangement of parts as claimed.

In the drawing forming part of this application like numerals of reference indicate similar parts in the several views and wherein:

Figure 1 is a side elevation of the device showing how a cigarette is removed from its receptacle.

Figure 2 is a sectional view taken on line 2-2 of Figure 1.

Figure 3 is a fragmentary view similar to Figure 1 showing the position of parts prior to the removal of the cigarette from its receptacle.

Figure 4 is a fragmentary view showing the operating lever and its mounting in elevation.

Referring to the drawing in detail 10 indicates a receptacle which may be constructed from any suitable material and also vary in size and configuration without departing from the inventive idea. The receptacle, however, is provided with spaced parallel depending portions 11 to provide a restricted passage to receive a number of cigarettes 12 in column-like formation, this passage being open at its bottom so that the cigarettes can be singly removed therefrom. One of the parallel portions 11 is slotted at its lower end as at 13 to receive a substantially bowed flat spring 14 which passes beneath the open bottom of the receptacle to support the cigarettes therein. This spring 14

is secured at its upper end in any suitable manner as at 15 upon one side of the receptacle. The spring permits the lowermost cigarette to be removed from the receptacle in the manner to be hereinafter described, and subsequently supports the remaining cigarettes within the receptacle.

Projecting from one end of the receptacle is a plate 15' on which is mountd a lever including the angularly disposed branches 16 and 17 respectively, the lever being pivoted upon the plate 15' as at 18. The branch 17 of this lever projects below the plate 15' and is connected with the adjacent end of an elongated plate 19 utilized to singly remove the cigarettes from the receptacle 10. The lower portion of the plate 19 carries a pin 20 which is received by a slot 21 in the lower end of the branch 17 of the lever. The plate is also supported for tilting and sliding movements upon the plate 15', by means of a pin 22, carried by the plate 15' and operating in an angular-shaped slot 23 formed in the plate 19. Projecting from the lower end of the plate 19 is a pointed element 24 located to pierce one end of the lowermost cigarette 12 of the column of cigarettes supported in the lower portion of the receptacle, and to subsequently remove the cigarette upon operation of the lever.

In practice the receptacle is filled with cigarettes 12, a number of which will be supported in column-like formation in the restricted passage defined by the intervening space between the parallel portions 11. When it is desired to singly remove the lowermost cigarette of the column of cigarettes, it is only necessary to depress the branch 16 of the lever, causing the plate 19 to assume the position illustrated in Figure 3, the plate assuming this position by reason of the slot 23 and the slot and pin connection between the plate and the lower end of the branch 17 of the lever. As the plate 19 assumes the position shown in Figure 3 the pointed element 24 pierces the adjacent end of the lowermost cigarette 12, so that when the branch 16 of the lever is elevated, the plate 19 is shifted to the position illustrated in Figure 1, and thereby removes the lowermost cigarette 12 from the

open bottom of the receptacle. Just as soon as the cigarette is removed, against the tension of the spring 14, the latter assumes its normal active position to support the remaining cigarettes within the receptacle.

While it is believed that from the foregoing description the nature and advantages of the invention will be readily apparent, I desire to have it understood, that I do not limit myself to what is herein shown and described and that such changes may be resorted to when desired as fall within the scope of what is claimed.

What is claimed is:

15 1. A device of the character described comprising a receptacle adapted to contain cigarettes, and including a restricted open lower portion to receive said cigarettes in column-like formation, means for supporting 20 said column, a plate projecting from one end of the receptacle, a pin projecting from said plate, a member having an angular-shaped slot receiving said pin, whereby said member is pivotally and slidably mounted on one side 25 of said plate, and constructed to pierce the adjacent end of the lowermost cigarette of the column in one position, and to remove the cigarette from the receptacle when shifted to a reverse position, and means for operating said member.

2. A device of the character described comprising a receptacle adapted to contain cigarettes and including a restricted open lower portion to receive said cigarettes in column-like formation, means for supporting said column, a plate projecting from one end of the receptacle, a pin carried by said plate, a slotted member having an angular-shaped slot receiving said pin, whereby said member 40 is pivotally and slidably mounted on one side of the plate, and including a pointed element projecting from one end thereof and adapted to pierce one end of the adjacent cigarette and to remove it from the receptacle as said member is moved in reverse directions, and means for operating said member.

3. A device of the character described comprising a receptacle adapted to contain cigarettes, and including a restricted open lower portion to receive said cigarettes in column-like formation, means for supporting said column, a plate projecting from one end of the receptacle, a slotted member pivotally and slidably mounted on one side of the plate and including a pointed element projecting therefrom, a lever pivoted on the other side of the plate and having a slot and pin connection with the lower end of the member, whereby the latter can be moved in reverse directions 60 to cause said pointed element to pierce one end of the adjacent cigarette and remove it from the receptacle.

In testimony whereof I affix my signature.
